UNITED STATES PATENT OFFICE.

ALFRED G. BROWN, OF LOS ANGELES, CALIFORNIA, ASSIGNOR TO UNION FIBRE COMPANY, OF WINONA, MINNESOTA, A CORPORATION OF MINNESOTA.

INSULATING-FLOOR.

1,229,407.

Specification of Letters Patent. Patented June 12, 1917.

Application filed April 17, 1914. Serial No. 832,506.

To all whom it may concern:

Be it known that I, ALFRED G. BROWN, a citizen of the United States, residing at Los Angeles, in the county of Los Angeles and State of California, have invented certain new and useful Improvements in Insulating-Floors, of which the following is a specification.

My invention relates to improvements in insulating floors intended particularly for use in refrigerator cars.

The problem of floor insulation for refrigerator cars involves the provision of two essential requirements: heat insulation and waterproofing. The insulation must be such as to prevent the interior of the car from becoming heated from the outside, and the waterproofing must be such as to prevent the water which collects upon the car floor from the melting of the ice and other causes from wetting, rotting and spoiling the heat insulation and the side sills and other timbers which support the car flooring. It has been customary heretofore to use a fibrous heat insulation, such as linofelt, hair felt, and the like, which is not in itself waterproof, and to cover this insulation with waterproof compounds and sheets of various sorts, which do not themselves have heat insulating properties.

It is the object of this invention to simplify the construction of waterproof insulating floors for refrigerator cars, by the use of an insulating filler which is in itself waterproof, the filler having such other qualities and characteristics that the construction is not only simplified but provides an insulation whose effectiveness is equal to, if not greater than, that of any insulating construction for floors known to me. In carrying out my invention, I preferably make use of the material well known in the art as "waterproof lith," the said "waterproof lith" being a material composed of mineral wool and vegetable fibers intermediately intermingled and waterproofed. This waterproofed material is commercially provided in self-sustaining sheets of practical thickness and having considerable tensile strength. Added to its waterproof and insulating qualities, its texture is such that spikes driven into it have no injurious results, since the material has no capillary attraction. The sheets are readily sawed, or otherwise cut and fitted, the inherent resili-

ency thereof making it an easy matter to make close or "crowded" joints with adjacent pieces of the material or with the wood against which it abuts, the joints thus provided being air-tight and readily water-proofed.

In prior insulating floor constructions known to me, it is common for the water which overflows from the drip-pans to not only soak and rot and otherwise detrimentally affect the insulation of the floors, but also to rot the side-sills which support the feet of the car-braces to the extent that when the car is subjected to severe bumping strains, the rotten sills give way so that the whole superstructure becomes loosened, thereby necessitating the practical rebuilding of cars. By the construction herein-after described, the sills are protected in an effective and economical manner, all but one of the false floors necessitated in high grade refrigerator car constructions now in use being eliminated, and the insulating construction interfitting with the side-sills in a manner which wholly protects the latter from contact with the moisture which may reach the refrigerator car floor.

With these objects in view my invention consists in the construction, combination and arrangement of parts hereinafter described and claimed.

In the accompanying drawings showing an embodiment of the invention.

Figure 1 is a vertical cross section through the car floor and part of the side walls of the car, with the invention applied thereto; and

Fig. 2 is a cross section on an enlarged scale of a fragment of the floor and one of the side walls.

In the drawings 2 represents the side sills and 3 the intermediate sills arranged at spaced intervals between the outer sills. 4 represents a false flooring supported partly upon the sills 3 and partly upon cleats 5 upon the inner sides of the outer sills. Upon the false flooring is preferably, but not necessarily, laid waterproof paper 6. Upon this flooring, or upon the waterproof paper placed thereon, are secured sub-sills 7 in position to overlie and aline with the sills 3. The outer sills 2, which extend up beyond the finished floor 8, are cut away on their inner sides to form shoulders 9 of the same height above the false flooring as the sub-

sills 7. Upon these sub-sills as well as upon the shoulders 9 of the outer sills is laid about half an inch of waterproof lith 10; while between the outer sills and sub-sills is tightly packed and fitted waterproof lith 11 to a height of about three eights of an inch above the level of the sub-sills and the shoulders of the outer sills, the material being cut so that it must be crowded into position, the resiliency thereof permitting this tight packing. Thus the lith insulation will be about an eighth of an inch higher upon the sub-sills and outer sills than in the intervening spaces, so that most of the weight of the finished floor 8 will be carried on the sub-sills and outer sills. Next the entire surface of the lith is preferably flooded with a suitable waterproof cement or coating 12, and the finished floor 8 laid thereon.

It will be observed that the outer portions of the side sills extend up above the top of the finished floor line, and that the floor 8 does not extend quite to this upwardly projecting portion 13, so a space is left to be filled in with waterproof cement 14, whereby the joint between the floor and the outer sill will be effectually sealed.

The side wall of the car may be insulated in any desired way, but, to safeguard the floor construction, one or more sheets 15 of lith are preferably used around the sides and ends of the car next to the floor, and cemented to the same by means of a suitable waterproof material.

Waterproof lith is particularly well adapted for the floor insulation on account of the ease with which the sheets of lith can be sawed and fitted around the frame and uprights. It may be added that it is the object of the present invention, not only to construct the heat insulation itself of waterproof lith or other fibrous waterproof material, but to simplify and improve the whole construction of the insulating floors for refrigerator cars, which is made possible by the use of such material.

I claim as my invention:

1. An insulating floor for refrigerator cars comprising in combination, side sills having bearing surfaces, sills arranged at intervals between said side sills and having bearing surfaces alined with the bearing surfaces of said side sills, sheets of waterproofed heat insulating material cut and fitted to the spaces between all of said sills including the side sills, sections of said insulating material also fitted upon and covering the bearing surfaces upon said sills and jointing with the material between said sills, and a finish floor laid upon said insulating material.

2. An insulating floor for refrigerator cars, comprising in combination, side-sills having bearing surfaces, a false flooring carried by said side-sills, sub-sills carried by said false floor and having bearing surfaces

aligned with the bearing surfaces of said side-sills, an insulating material fitted between said sub-sills, and said sub-sills and side-sills, sections of said insulating material also fitted upon said bearing surfaces, and jointing with the material between the sills and a finish floor laid upon said insulating material.

3. An insulating floor for refrigerator cars, comprising in combination, side-sills, sub-sills laid between said side-sills, a false flooring carried by said side-sills and having said sub-sills laid thereupon, an insulating material cut and fitted to the spaces between said sub-sills, sections of said insulating material also cut and fitted to provide insulated seats on said sub-sills and side-sills, a layer of water proofing material flowed over all of said insulating material and a finish floor laid over said layer of water-proofing material and having its weight distributd over said sections.

4. An insulating floor for refrigerator cars, comprising in combination, side-sills, sub-sills between said side-sills, a false flooring supported by said side-sills and carrying said sub-sills, an insulating material cut and fitted to the spaces between said sub-sills, sections of said insulating material also cut and fitted on said side-sills and sub-sills and providing bearing surfaces above the level of the first mentioned insulating material and a finish floor laid upon said bearing surfaces.

5. An insulating floor for refrigerator cars, comprising in combination, side-sills, sub-sills between said side-sills, recessed shoulders provided on said side-sills and forming bearing surfaces in alinement with the upper surfaces of said sub-sills, an insulating sheet material cut and fitted to the spaces between the sills, sections of said insulating material also cut and fitted to said bearing surfaces and the upper surfaces of said sub-sills, a flooring laid over the insulating material on said sub-sills and said recessed shoulders, the insulating material thereon and said flooring forming an insulating joint with the side construction of the car.

6. An insulating floor for refrigerator cars comprising in combination, side sills, sills arranged at intervals between said side sills, sheets of waterproofed heat insulating material cut and fitted to the spaces between all of said sills, including the side sills, sections of said insulating material also cut and fitted upon said sills and providing bearing surfaces above the level of the insulating material between the sills, and a finish floor laid upon said bearing surfaces.

7. An insulating floor for refrigerator cars, comprising in combination, side sills, sills arranged at intervals between said side sills, said side sills having recessed shoul-

ders forming bearing surfaces in alinement with the upper surfaces of said intervening sills, sheeted, waterproofed, heat insulating material cut and fitted to the spaces between
5 all said sills including the side sills, sections of said insulating material also cut and fitted to said bearing surfaces upon the side sills and the upper surfaces of the other sills, and covering the same, a flooring laid over
10 said insulating material on said sills and

recessed shoulders, said flooring and the insulating material upon said recessed shoulders forming an insulating joint with the side construction of the car.

In testimony whereof I affix my signature 15
in presence of two witnesses.

ALFRED G. BROWN.
